Edward K. Tolman

UNITED STATES PATENT OFFICE.

EDWARD K. TOLMAN, OF WORCESTER, MASSACHUSETTS.

KEY-FASTENER.

SPECIFICATION forming part of Letters Patent No. 269,744, dated December 26, 1882.

Application filed August 28, 1882. (No model.)

To all whom it may concern:

Be it known that I, EDWARD K. TOLMAN, a citizen of the United States, residing at Worcester, in the county of Worcester and State of Massachusetts, have invented a new and useful Improvement in Lock-Escutcheons, of which the following is a specification.

My invention relates to a lock-escutcheon by which the key may be held and securely fastened in the lock, and also by which the key-hole may be closed when the key is not in the lock; also, to a mode of preventing the escutcheon from being operated from the opposite or under side by a knife or sharp-pointed instrument; and my invention is fully set forth in the following specification and accompanying drawings, in which—

Figure 1 shows a lock with my escutcheon attached; Fig. 2, an enlarged view of the escutcheon; Fig. 3, a front view of the same, showing the mode of operation. Fig. 4 is a sectional view on line *x x*, and Fig. 5 a sectional view on line *s s*.

Similar letters refer to similar parts in the several views.

My escutcheon consists of two plates of circular or other suitable form, the plate *A'* being fastened by screws to the door, and having a key-hole, *D*, and a curved slot, *G*, shown by the broken lines in Figs. 1, 2, and 3. The second plate, *A*, is pivoted at *B* to plate *A'*, and has a key-hole, *C*, and a straight slot, *E*, opening out of the key-hole *C*, a stud, *F*, passing through the slot *G*, by which the swinging motion of the plate *A* is limited, and a knob or handle, *F*, by which the plate may be moved, as shown in Fig. 3, so that the key-holes in the two plates will correspond. The key is then inserted and turned, throwing the bolt until the handle of the key stands as shown at *I* in Fig. 1, when the plate *A* is moved back to correspond with plate *A'*, with the key inclosed in and held from turning by the slot *E*. As the screw *H'* in the plate *A'* is covered by the plate *A*, I make a hole, *H*, in plate *A*, so it will uncover the screw when the plate *A* is moved to the position shown in Fig. 3, and afford access to the screw. Otherwise the plate *A* would have to be removable.

When the two plates coincide as in Figs. 1, 2, holding the key in the slot *E*, it would be possible to enter a knife or pointed instrument through the opposite key-hole, and by pressing the point into the under surface of *A* to move it back, as shown in Fig. 3, causing

the key-holes to correspond, when the key may be turned or pushed out. In order to prevent this I form notches *ff* at the inner end and on the sides of the curved slot *E*, and also form two wings on the opposite sides of the stud 60 or pin *F'*, so they coincide with the notches *ff* when the key is locked in; and any pressure against the under side of the plate *A* will push the plate away from the plate *A'*, the pivoted joint at *B* being made loose enough for that 65 purpose, thereby drawing the wing on the end of the stud *F'* into the notches *ff*, a slight resistance at that point effectually preventing the plate from being moved in the manner indicated.

It will readily be seen that when the escutcheon is applied directly to the body of the lock, the plate *L* may form the lower or plate *A'* by making a slot, *G*, having notches *ff*.

By using a plate, *A*, having a key-hole, *C*, 75 arranged as described, I am able to form the two plates *A* and *A'* of the same shape and size, so that their outlines will coincide when the key is locked in, thereby presenting a neat and slight appearance.

What I claim as my invention, and desire to secure by Letters Patent, is—

1. A lock-escutcheon consisting of two plates, *A* and *A'*, pivoted together at *B*, the plate *A'* having a slot, *G*, curved concentrically with 85 the pivot *B* and a key-hole, *D*, and the plate *A*, having a key-hole, *C*, straight slot *E*, and stud *F*, sliding in the slot *G*, as described, and for the purpose set forth.

2. A lock-escutcheon consisting of two 90 plates, *A* and *A'*, pivoted together loosely at *B*, so as to allow the plates to be separated slightly at the side opposite the pivot, the plate *A'* having a key-hole, *D*, and slot *G* curved concentrically with the pivot *B*, said 95 slot having at one end the notches *ff*, and the plate *A* having a key-hole, *C*, straight slot *E*, and a stud, *F*, entering the curved slot *G*, said stud having wings fitting the notches *ff*, and arranged as shown and described, whereby, when the key is held by and in the slot *E*, pressure against the under side of the plate *A* will cause the wings to be drawn into the notches *ff*, securely locking the two plates *A'* and *A* together as long as the pressure is applied, as and for the purpose set forth.

EDWARD K. TOLMAN.
